(57) **CLAIM**

The ornamental design for a dosing pump for chemicals and liquids as shown and described.

DESCRIPTION

The patent or application file contains at least one drawing executed in color. Copies of this patent or patent application publication with color drawing(s) will be provided by the Office upon request and payment of the necessary fee.

1. Dosing pump for chemicals and liquids

2. Dosing pump for chemicals and liquids

3. Dosing pump for chemicals and liquids

4. Dosing pump for chemicals and liquids

1. The name of this design product: dosing pump for chemicals and liquids; 2. Purpose of the product with this design: for high precision dosing of chemicals, enabling advanced control of process and integration with system control; 3. The main points of the design of the product are: the overall shape of the product; 4. The picture or photo that best shows the main points of the design: reproduction No. 1.1 perspective view.
